UNITED STATES PATENT OFFICE

JOSEPH W. HOLLIDAY, OF RED WING, MINNESOTA

CURRENCY TRAY

Application filed March 28, 1930. Serial No. 439,844.

This invention relates to currency trays or drawers for bank tellers, cashiers, and the like.

With most currency trays used at this time it is somewhat difficult to remove the bills and the currency in the compartments often becomes disarranged in so doing. These difficulties are increased at the present time due to the fact that our Government has recently 10 decreased the size of its currency.

Most of the currency holders used at this time comprise spaced compartments wherein the bills are disposed horizontally at the bottom thereof. The teller's hand must be inserted close to the bottom of the tray to pick up the currency and his hand must be disposed directly above the top of the tray in order to determine the denominations of the different bills in the compartments.

20 It is an object of my invention to provide a simple and highly efficient currency tray or drawer, wherein the several compartments are so constructed that the bills will be held in edgewise position inclined slightly from the vertical and with their upper edges alined to facilitate removal thereof.

It is a further object to provide a currency tray of the class described, wherein the denominations of the bills in the several compartments can instantly be ascertained from one end of the tray or drawer.

Another object is to provide a currency tray wherein the bills in the several compartments cannot become displaced from one 35 compartment to the other and will be protected from disturbance by wind and draft, and wherein the bills will not be disarranged when one or more bills are withdrawn.

Still a further object is to provide an efficient currency tray of the class above described, which may be manufactured at low cost, and which is adapted to be utilized in connection with standard equipment for bank tellers and cashiers employed at the 45 present time.

These and other objects and advantages of the invention will be apparent from the following description made in connection with the accompanying drawings wherein like reference characters refer to similar parts

throughout the several views and wherein,

Fig. 1 is a plan view of an embodiment of the invention, one of the compartments having a number of bills disposed therein;

Fig. 2 is a cross section taken on the line 55 2—2 of Fig. 1;

Fig. 3 is a vertical section taken on the line 3—3 of Fig. 2; and

Fig. 4 is a perspective view of my device on a smaller scale.

The particular embodiment of the invention illustrated includes a rectangular box frame open at its top and bottom and having side walls 6 and end walls 7. The space within the box frame is divided into a plurality of bill holding compartments. Each compartment is defined by an inclined bottom 8 extending transversely of the box and a back 9 disposed substantially at right angles to bottom 8. The back 9 of each compartment is provided with upwardly projecting extensions or guides 10, which lie in the same plane therewith and terminate at points a slight distance below the upper edge of the box frame.

As shown, each compartment is provided with a pair of said extensions or guides and these extensions constitute a part of the rear support for one compartment and also the forward partitions for the compartment disposed at the rear thereof. The extensions or guides are each spaced a short distance from one of the sides 6 of the box frame in order that the denomination of the bills in the compartment at the rear thereof may be observed.

The bottoms 8, as shown, are inclined at an angle of approximately 30 degrees to the lower longitudinal edge of the box, although this angle may, of course, be varied considerably, all within the scope of the invention.

In the particular embodiment shown, the component parts of the several compartments including the bottoms 8, backs 9, and extensions 10 are all integrally formed from a single piece of sheet material, such as sheet metal, the strip being bent upwardly at right angles on lines α to form the backs 9 and bent downwardly at right angles on lines γ to form the bottoms 8 of the several compartments. The extensions or guides 10 are cut out from

the bottom portions 8 of the next rear compartments and extend in the same plane with the backs 9, the cutting out of said extensions leaving openings z in the bottom of each compartment, which openings, as shown, extend substantially from the lines x to y and allow dirt to drop therethrough.

The sheet of material which defines the bottoms, backs and guides of the compartments may be secured to the box frame in any suitable manner and, as shown, this is accomplished by extending the ends of the bottom portions 8 and bending the extensions downwardly to form flanges 8a, which may be spot welded or otherwise secured to the sides 6 of the box frame. One end of the sheet of material is provided with a downturned flange 8b which may be secured to one of the ends 7 of the box frame, while the opposite ends of the sheet of material is provided with a downturned flange 9a, which is secured to the opposite end of the box frame.

Bills are disposed in the compartments, as illustrated in the drawings, the compartments being of slightly greater length than the bills and thereby holding the bills against longitudinal displacement while the lower edges of the bills rest upon the bottom of the compartment, gravity thus causing the upper edges to be alined since the bottom of each compartment is disposed at right angles to the slightly inclined back and extension.

Regardless of whether the compartments are filled or only partially filled, the denominations of the bills in the several compartments will all be clearly displayed through the space between the extensions or guides and the side walls 6 of the box frame. When one compartment is filled the first bill in that compartment will have its edge disposed a considerable distance above the upper edge of the rear bill in the next forward compartment. This enables the denominations of the bills, as well as the pictures on the bills, which are disposed in the compartments between the extensions or guides to be observed from the forward end of the tray.

One or more bills may be quickly selected and withdrawn from the compartments since the upper edges of the bills in each compartment are substantially alined and this may conveniently be accomplished by grasping the upper edge of the desired bill or bills with the thumb and forefinger disposed in the space between the two extensions or guides of the compartment.

Gravity keeps the bottom edges of the bills together and because of the inclined bottoms 8 of the compartments the bills will not spread apart or slide over one another and consequently will never be disposed flat against the bottom, even though only one or two bills are held in a compartment.

The guides positively prevent the bills sliding from one compartment to another dur-

ing the many operations of opening and closing the drawer or in the event that a draft strikes the tray.

From the foregoing description it will be seen that I have provided a simple and highly efficient currency tray which eliminates the objectionable features common to trays extensively used at this time in banks and which facilitates the handling of currency and permits the teller or cashier to readily observe the denominations of the bills in the various compartments from the forward end of the tray.

It will, of course, be understood that various changes may be made in the form, details, arrangement and proportions of the parts without departing from the scope of my invention, which, generally stated, consists in a device capable of carrying out the objects above set forth, such as shown and described and defined in the appended claims.

What is claimed is:

1. In a currency tray, a series of bill holding compartments each comprising a bottom inclined from the horizontal, and a back disposed at least at 90° with relation to said bottom, said back being of less height than the width of a bill, and extensions or guides projecting upwardly from said back and lying in substantially the same plane therewith, said extensions constituting front partitions for the adjacent rear compartments.

2. In a currency tray, a series of bill holding compartments having spaced ends, each compartment including a bottom inclined from the horizontal and a back extending at an angle to said bottom, and of less height than the width of a bill, and spaced extensions or guides projecting upwardly from said back and lying in substantially the same plane therewith.

3. In a currency tray, a frame including a pair of spaced substantially vertical walls, a series of bill holding compartments disposed transversely between said walls, said walls constituting the ends for said compartments, each of said compartments including a bottom inclined from the horizontal, and a back extending upwardly from said bottom at an angle of at least 90° thereto and being of less height than the width of a bill, and extensions or guides projecting upwardly from said back and lying substantially in the same plane therewith, said extensions being spaced apart to facilitate removal of the bills and to render visible, portions of the bills in the next rearward compartments.

4. In a currency tray, at least a pair of bill holding compartments having vertical ends spaced apart a distance slightly greater than the length of a standard bill, each of said compartments having a bottom inclined from the horizontal, and a back extending from said bottom at an angle thereto, the height of said back being less than the width of a bill, said backs having extensions project-

ing upwardly and lying in a plane substantially coincident therewith and being spaced laterally from the ends of said compartments to disclose the printed denominations in the corners of bills disposed in the next rearward compartment.

5. In a currency tray, a series of bill compartments constructed from an integral sheet of material bent on parallel lines to form bottoms inclined from the horizontal and backs for each compartment extending at substantially 90° angles with respect to said bottoms, and extensions or guides projecting upwardly from said backs and in planes coincident therewith, said extensions being cut from the bottom portions of the next rearward compartment.

6. In a currency tray, a series of bill compartments, constructed from an integral sheet of material bent on parallel lines to form bottoms inclined from the horizontal, and backs for each compartment extending at substantially a 90° angle with respect to said bottoms, extensions or guides projecting upwardly from said backs and in planes coincident therewith, said extensions being cut from the bottom portions of the next rearward compartments, and a rectangular box frame having spaced sides and ends, connections between the edges of the sheet from which said compartments are formed and the sides and ends of said box frame, whereby the sides of said frame will form the ends of said compartments.

35. In testimony whereof I affix my signature.
JOSEPH W. HOLLIDAY.
